[57] CLAIM

The ornamental design for a zero clearance fireplace, as shown and described.

DESCRIPTION

FIG. 1 is a perspective view of a zero clearance fireplace showing our new design, the broken line showing of environmental structure being for illustrative purposes only and forming no part of the claimed design;

FIG. 2 is a front view of the zero clearance fireplace of FIG. 1; and,

FIG. 3 is a top cross-sectional view of the zero clearance fireplace taken along line 3—3 of FIG. 2.
